(57) **CLAIM**

I claim the ornamental design for communication device, as shown and described.

DESCRIPTION

FIG. 1 is a perspective view of a communication device in a closed position according to the present invention.

FIG. 2 is a top plan view of the communication device of FIG. 1.

FIG. 3 is a first side elevational view of the communication device of FIG. 1.

FIG. 4 is a second side elevational view of the communication device of FIG. 1.

FIG. 5 is a front elevational view of the communication device of FIG. 1.

FIG. 6 is a bottom plan view of the communication device of FIG. 1.

FIG. 7 is a rear elevational view of the communication device of FIG. 1.

FIG. 8 is a perspective view of the communication device of FIG. 1 in an open non-extended position.

FIG. 9 is a top plan view of the communication device of FIG. 8 showing an interior surface thereof.

FIG. 10 is a first side elevational view of the communication device of FIG. 8.

FIG. 11 is a second side elevational view of the communication device of FIG. 8.

FIG. 12 is a front elevational view of the communication device of FIG. 8.

FIG. 13 is a bottom plan view of the communication device of FIG. 8 showing an exterior surface thereof.

FIG. 14 is a rear elevational view of the communication device of FIG. 8.

FIG. 15 is a perspective view of the communication device of FIG. 1 in an open fully-extended position.

FIG. 16 is a top plan view of the communication device of FIG. 15 showing an interior surface thereof.

FIG. 17 is a first side elevational view of the communication device of FIG. 15.

FIG. 18 is a second side elevational view of the communication device of FIG. 15.

FIG. 19 is a front elevational view of the communication device of FIG. 15.

FIG. 20 is a bottom plan view of the communication device of FIG. 15 showing an exterior surface thereof; and,

FIG. 21 is a rear elevational view of the communication device of FIG. 15.
